UNITED STATES PATENT OFFICE

ALBERT D. BINGHAM, OF NEW HAVEN, CONNECTICUT.

WATCH-MOVEMENT.

SPECIFICATION forming part of Letters Patent No. 323,777, dated August 4, 1885.

Application filed August 16, 1884. (No model.)

To all whom it may concern:

Be it known that I, ALBERT D. BINGHAM, of New Haven, in the county of New Haven, and in the State of Connecticut, have invented 5 certain new and useful Improvements in Watch-Movements; and I do hereby declare that the following is a full, clear, and exact description thereof, reference being had to the accompanying drawings, in which—

10 Figure 1 is a plan view from the rear side of a watch-movement containing my improvements, the back plate being removed. Fig. 2 is a like view of the same from the front side, the dial and mainspring being removed. Fig. 15 3 is a plan view of said movement from the rear with all of the train removed except the main wheel and the dial-wheels with their bridge. Fig. 4 is a perspective view of the intermediate dial-wheel with its bridge separated from the other parts of the train. Fig. 20 5 is a like view of the cannon-pinion, hours-wheel, and main wheel, and arbor separated from each other, and Fig. 6 is an enlarged section upon line $x-x$ of Fig. 3.

25 Letters of like name and kind refer to like parts in each of the figures.

My invention is an improvement upon a watch-movement which was patented December 27, 1881, No. 251,532, and has for its object 30 the driving of the hands through the usual dial-wheels, whereby I am enabled to set said hands in the ordinary manner instead of separately, as heretofore.

To this end my said invention consists in 35 the construction, arrangement, and combination of parts as hereinafter specified.

In the annexed drawings, A represents the front or pillar plate of a watch, which is connected with a back plate by pillars B or in 40 any usual and well-known manner. Said pillar-plate has the whole of its front side recessed for the reception of a mainspring, C, and within its center is journaled an arbor, D, that upon its front end is provided with a 45 spring-collet, d, and upon its rear end has a toothed wheel, d', through which the power of the spring is communicated to a time-train of usual construction and arrangement.

The arbor D is hollow, and within the same 50 is loosely journaled the sleeve e of an hours-hand wheel E, which latter is placed imme-

dately in rear of the main wheel d', with said sleeve extending forward a sufficient distance to enable an hours-hand, F, to be placed upon its end in the usual manner. 55

Journalized loosely within the sleeve e is a cannon-pinion, G, which, at its outer end, is adapted to receive a minutes-hand, F', and axially to receive the arbor h of the center or minutes-wheel, H, said arbor being held in engagement with said cannon-pinion by friction in the usual manner. The cannon-pinion G and hours-wheel E have the usual relative proportions, and are connected by means of an intermediate dial-wheel, I, and pinion 65 i, which latter are rigidly connected together, and are journaled upon the inner side of a supplemental bridge, K, that is secured upon the lower face of the pillar-plate A. The bridge K extends over the end of the cannon-pinion G, and serves to hold the same and the hours-wheel E in position. The center-wheel arbor h passes through said bridge, which thus operates as a journal-bearing for the front portion of the same. 70 75

The center wheel being connected with the time-train, the minutes and hours hands are driven in the usual manner, and in setting said hands a change in the position of the former is instantly communicated to the latter. The 80 arrangement of the dial-wheels below the pillar-plate enables their use without increase in the thickness of the movement, as the space occupied by them and by the bridge in no manner interferes with the other operative parts 85 of the train.

Having thus fully set forth the nature and merits of my invention, what I claim as new is—

1. In a watch-movement, the dial-wheels 90 driven from the minutes-arbor through frictional connection therewith, and having the cannon-pinion and the sleeve of the hours-wheel journalized axially within and passing through the mainspring-arbor, substantially 95 as and for the purpose set forth.

2. In a watch-movement, in combination with the dial-wheels placed immediately below the front or pillar plate, the minutes-arbor, a frictional connection between such arbor and wheels through which the wheels are driven 100 from the arbor, and the sleeve for the hours-

hand, and the barrel of the cannon-pinion for the minutes-hand passing forward axially through the mainspring, substantially as and for the purpose described.

5 3. In a watch-movement, in combination with the removable bridge attached to the back of the pillar-plate, the intermediate dial-wheel journaled wholly upon and removable with the bridge, substantially as and for the purpose described.

In testimony that I claim the foregoing I have hereunto set my hand this 4th day of August, 1884.

A. D. BINGHAM.
